UNITED STATES PATENT OFFICE.

EBEN S. DRAPER, OF HOPEDALE, MASSACHUSETTS, ASSIGNOR TO GEORGE DRAPER & SONS, OF SAME PLACE.

SUPPORT FOR SPINNING-SPINDLES.

SPECIFICATION forming part of Letters Patent No. 447,400, dated March 3, 1891.

Application filed April 23, 1889. Serial No. 308,281. (No model.)

To all whom it may concern:

Be it known that I, EBEN S. DRAPER, of Hopedale, county of Worcester, State of Massachusetts, have invented an Improvement in 5 Supports for Spinning-Spindles, of which the following description, in connection with the accompanying drawings, is a specification, like letters on the drawings representing like parts.

10 This invention has for its object to improve that class of spindle-supports wherein the bolster is made vertically adjustable with relation to the step, in order that the tapering inner surface of the bolster may be kept in 15 proper contact with the tapering surface of the spindle and the amount of looseness between the bolster and spindle be regulated. Prior to this invention, as in United States Patent No. 378,877, this adjustment has been 20 accomplished by connecting the lower end of the bolster with the upper end of the step by a screw-thread. In the patent referred to the thread at the lower end of the bolster is an internal thread, and the thread upon the upper end of the step is an external thread, and as a result of such construction the thread is necessarily fine and of less depth than were the bolster threaded externally and the step internally, for it will be understood that the 25 30 smaller the diameter of the circle occupied by the threads the less the depth to which the threads can be cut. By threading the bolster externally and the step internally it becomes possible to bring the threads uniting the bolster and step into a larger circle, and consequently the threads may be made deeper, the depth being such as to insure a sufficient looseness of engagement between the bolster and step to enable the bolster to 35 40 move as required by the spindle as the latter seeks its true center of rotation, the movement of the bolster when the lower end of the latter enters a hole in the step loosely rather than fitting over a projection being freer than 45 50 when the lower end of the bolster surrounds a projection, as in the patent referred to. Further, when the bolster is threaded externally to enter the step, as herein provided for, the connection between the bolster and step is more durable because of the coarse threads

than in the old plan represented in the patent referred to.

Figure 1, in partial elevation and section, shows a spindle and support for it embodying my invention; Fig. 2, a section below the dotted line x ; Fig. 3, a section in the dotted line x' , and Fig. 4 an elevation of the bolster.

The rail A, the supporting-case B, secured to it by the nut B', and the spindle C, having, as shown, a sleeve-whirl C' and tapered from 60 at or near the plane of the band-pull to its lower end, are and may be all as usual.

The chief purpose of the bolster a is to constitute a smooth hard-surfaced but yielding lateral bearing, against which the tapering 65 exterior of the pintle of the spindle may run and bear uniformly.

In practice it has been found of the greatest advantage to mount the bolster loosely in a supporting-case and to enable the bolster to 70 have greater looseness or freedom of motion than in the construction represented in the said patent, and also to increase the strength and durability of the parts I have provided the lower end of the bolster with an external 75 screw-thread and have tapped a hole into the step, and I have so cut the said screw-thread that the connection is very loose, yet the threads are so thoroughly cut and defined as to enable the bolster to be adjusted accurately 80 to the tapering surface of the spindle by rotating the bolster. When the lower end of the bolster surrounds an extension of the step, the bolster is prevented from tipping freely; but by threading the lower end of the 85 bolster externally and screwing it loosely into the step the bolster may tip freely on or with relation to the step to the extent of the looseness of the screw-threads, and the foot of the spindle may move laterally on the step below 90 the bolster sufficient to very materially decrease any tendency to jar.

I have shown the bolster as provided with a projection a' to enter a notch a^2 in the support B, and the step as notched at b' to receive a projection b^2 , such notches and projections restraining the rotation of the bolster and step with the spindle.

Both the bolster and step should preferentially be loosely fitted in the supporting-case, 100

though either may be fitted closely without departing from my invention.

I believe myself to be the first to enter a bolster into a step for the purpose of reducing jar when either member is loosely held, and consider this structure advantageous even if the screw-threads are omitted.

I am aware that in the patent referred to the screw-threads connecting the bolster with the step may be such as to leave considerable play between the threads; but with such construction the thread being at the interior of the bolster and at the exterior of the step, rather than at the exterior of the bolster and at the interior of the step, as herein provided for, makes such a fine thread, owing to the small diameter of the circle in which the thread falls, that the looseness is insufficient to provide for the necessary movement of the bolster.

I claim—

1. A spindle case or support and a spindle having a tapering pintle, combined with a bolster tapered internally to fit the spindle and threaded externally at its lower end, and with an independent step threaded internally and into which the lower end of the bolster is screwed loosely, substantially as described.

2. The combination, with a supporting case or holder and a step recessed at its upper end, as described, of an independent bolster, the lower end of which is inserted in the step loosely to permit lateral movement of the bolster in or with relation to the step, substantially as described.

In testimony whereof I have signed my name to this specification in the presence of two subscribing witnesses.

EBEN S. DRAPER.
